UNITED STATES PATENT OFFICE.

CHAUNCEY F. McCULLOH, OF BALTIMORE, MARYLAND.

DISTRICT-TELEGRAPH SYSTEM.

SPECIFICATION forming part of Letters Patent No. 253,080, dated January 31, 1882.

Application filed October 28, 1881. (No model.)

To all whom it may concern:

Be it known that I, CHAUNCEY F. McCULLOH, of Baltimore city, State of Maryland, have invented certain new and useful Improvements in District-Telegraph Systems; and I hereby declare the same to be fully, clearly, and exactly described as follows, reference being had to the accompanying drawings, in which—

Figure 1 is a plan view, illustrating the arrangement of apparatus in the central office in connection with several circuits. Fig. 2 is an elevation of the signal-box mechanism; Fig. 3, a plan of the device for making and breaking connection, and Fig. 4 a similar view of the switch and relays.

My invention relates to district-telegraph systems or fire-alarm telegraphs in which a number of stations are in circuit with a central office; and it has for its object to obviate what has heretofore been a source of great annoyance and of loss both of time and money.

In telegraph systems of the class referred to as heretofore constructed and used—with relays, registers, and gongs in the central office—the breakage of the line has either resulted in the cutting out of the stations beyond the break or in making the entire circuit inoperative until the break is located and repaired.

I have succeeded in remedying this evil and in producing a system in which the occurrence of a break is instantly signaled at the central station, where means are afforded for immediately making the entire circuit as efficiently operative as if no break had occurred. In a word, nothing short of two simultaneous breaks, one on each side of a station, can throw it out of communication with the central office, and even then the other stations of the same circuit are unaffected. This I accomplish by connecting the several stations of the circuit with the main office by wire, making a metallic circuit, and providing each station, as well as the central office, with a ground-connection. These ground-connections are all normally open, so that the occurrence of a break is instantly made known at the central office, where, the ground being then thrown on, a circuit is set up as each box is operated. Provision is also made at the central office for detecting an accidental grounding of either part

of the wire in case of a break, and for obviating it, so that both parts of the broken circuit are made operative in any event. The box at each station is provided with a device for simultaneously making and breaking connection with the main line and with the ground, whereby, while the line is intact, the current passes over the wire; but in the event of a break the return is through the ground. The occurrence of a break is instantly made apparent at the central office by the stroke of the gong and the starting of the register. It is obvious that the boxes on both sides of a break being grounded when in operation, all the signals are recorded, what was theretofore a closed metallic circuit becoming after the break two circuits, each having a ground-return. These circuits are just as efficient as the closed metallic circuit, and a single break is productive of no bad result. As soon as one occurs, however, a lineman is sent out to repair it, because, until this is done, a second break on either side of it will cut out all the intermediate boxes. This contingency can manifestly not be guarded against; but it is very remotely possible that a second break will occur before the first can be repaired.

In the accompanying drawings, Fig. 1, are shown the usual paraphernalia of the central office and their circuits $a a' b b' c c'$, having each a number of stations, A B C. These stations are all connected by a main-line wire with the office, where they are attached, as usual, to disk-switches 25 25' 25" of the ordinary construction. 22 is the local battery; 10, the No. 1 main battery; 11, No. 3 main battery; and 12, the extra battery, to be used on any of the circuits of the switch-board. The extra battery 12 is connected by the wire 1, leading through the relay 18, with the right lower segment of each of the upper-disk switches, the wire from the other pole of the battery leading through the relay 17, by the wire 2, to the corresponding segment of each of the lower disks. The No. 1 (10) main battery is connected by wire 3 with its relay 24, from which the wire 3 continues to the left lower segment of the disk 25, which latter is normally in electric connection with the upper half of the disk through a plug, 26. From the upper half of the disk the current traverses the line $a a'$, returning to the

upper half of the lower disk 25, which is connected with the left lower segment of the same by a plug, 27, and thence by the wire 4 to the battery. Such is the normal arrangement of the circuit $a a'$ with reference to the battery 10 and disk-switches 25, and it is the usual and well-known arrangement. Double cords 5, 5, having split plugs on their ends, connect the first circuit, $a a'$, with the second, $b b'$, as shown. The third circuit, $c c'$, is connected from the upper half of the disk 25'', by plug 28, with the left lower segment of the upper disk; thence the current passes by wire 6, through relay 23, to one pole of the battery 11, No. 3. From the opposite pole the wire 7 leads to the left lower segment of the lower disk 25''; thence through the plug 29 to the upper half of the disk and wire c . The wire 8 from the local battery 22 leads primarily to the relay 23, which closes circuit with the wire 9, leading to the gong 15 and register 16 of the circuit $c c'$; thence the current returns, by the wire 8', to the other pole of the battery. The other circuits, $a a' b b'$, are connected, as usual, with the local battery and their relay 24, gong 13, and register 14. From the wire 8' leads a tap or loop, 9', to the register 21, gong 20, relays 18, 17, and by wire 10' the current is led to the wire 8 and to the opposite pole of the local battery. From the center cell of the extra battery 12 leads a wire, 30, to a double-lever switch, 19, having a ground-connection, G' . From the switch 19 lead wires 37, 38 to the wire 2, as shown. Each station A B C is provided with a normally-broken ground-connection, G .

Such is the general arrangement of the apparatus, and its operation may well be described before going into a detailed description of the box mechanism shown in Figs. 2 and 3. Suffice it here that the latter has a ground-connection, normally broken, but so arranged as to close to make the signal. Now suppose a break to occur in any of the circuits—say at X in the line $c c'$ —the current is immediately broken, and notice is given at the central office by the stroke of the gong 15 and the starting of the register 16, precisely as if the first break of a signal had come in. The plugs 28 and 29 are simply moved over to connect the upper halves of the disks 25'' with the right-hand lower segments, and the double-lever switch 19 is thrown over from its normal position (shown in dotted lines, Fig. 4) to the position shown in heavy lines, Figs. 1 and 4. This has the effect of throwing the relay 17 into circuit and of grounding the center of the battery 12 by wire 30, the transposition of the plugs 28, 29 having changed the main circuit from battery 11 to extra battery 12. Each of the relays 17, 18 is provided with three disks, 32, 33, 34. The disks 34 are connected together and with the wire 9' from one pole of the local battery, the armatures 35 being connected with the wire 9' to the other pole of the same battery. The disks 32 are connected with the insulated contact-pins 36 of the relays, and

the disks 33 are connected with the metallic frames sustaining the pins 36. Each relay has a plug, 31, to fit between the disks and set up electric connection. The position of the plugs 70 with reference to the disks 32, 33, and 34 determines the action of the relay, making it work on either the forward or backward stroke, as may be necessary in the event of the grounding of the wire in case of a break. 75

The object of grounding the center of the battery 12 and of locating a relay on each side of it is to guard against the contingency, in the event of a break of the line, of a permanent ground being thrown on at one end, as is very 80 liable to occur should the broken wire fall on a lightning-rod or into the street. In the latter case the grounding is liable to be due to contact of the wire with street-car rails, a lamp-post, or awning-support. Obviously, 85 should both ends be grounded, the circuit would be unimpaired; but this is most unlikely to occur.

The break is supposed to occur at X, and neither end of the wire grounds. The operator in the central office turns the switch 19 and moves the plugs 28, 29, as before described, and removes the pin 31 of the relay 18 from its normal position between the disks 32 and 34, and inserts it between 34 and 33, as shown. This 90 has the effect to establish connection as follows: From the ground—say at the right of the break—the current passes through the wires c' 1 to relay 18, to battery 12, thence through wire 30 to switch 19, and to ground G' . From a box 100 to the left of the break the current traverses the wires c , 2, relay 17, to battery 12, to wire 30, and to ground G' . Now suppose a break at X, and the end of the wire to the left grounds on a lightning-rod or otherwise, the current to the 105 right of the break traverses the course above stated, but to the left a continuous ground-circuit is supposed to have been set up. The pin 31 on relay 17 is simply moved to the hole between the disks 34 and 32, causing the relay 110 to work on the backward stroke as before the break. The insertion of the pin between the disks 34 and 32 has the effect to establish the circuit from the wires 9' to the armature, and thence through the contact-screw 36 to the disk 115 32, so that circuit is closed as the armature flies back, whereas when the pin is between the disks 34 and 33 the circuit is set up on the forward stroke through the armature-post and the other screw. Of course in case of a ground to 120 the right of the break at X the same transposition of the pin on the relay 18 is made. Should both ends ground, no movement of the pins is necessary, as the line is then practically intact. The gong sounds a single stroke 125 at the instant of the break, and the register starts, but instantly stops when the ground is set up. Tracing out the course of the current, for the sake of clearness, we have in the supposed case a break at X and an accidental 130 grounding of the end at the left of the break. The current passes through the wire c to the

upper half of the disk, through the plug 29, which has previously been moved to the right, to the right-hand lower half of the disk, through wire 2 to extra relay 17, thence by the 5 other wire 2 to the battery 12, by the wire 30 to switch 19, and to the ground. The closing of the circuit has the effect to bring the armature of the relay 17 against the contact-pin above the magnets, closing the circuit as follows, viz: through the armature, wires 9' 8', to battery 22, thence by wires 8 and 10' to disk 34, thence through plug 31, to disk 33, to post, which holds the pin against which the armature rests. As a result, the gong 20 gives one 15 stroke and the register 21 starts running. The plug 31 is immediately moved to the hole between the disks 34 and 32, breaking the local circuit. As any box to the left of the break is now operated its circuit-closer makes and 20 breaks circuit on the disk, the breaking of the circuit as it passes between the teeth allowing the armature on the relay 17 to fly back against the contact-pin 36. As it touches the pin, local circuit is set up as follows: through the armature, wires 9' 8', to battery 22, thence by wires 25 8 and 10' to disk 34, by pin 31 (which is now between 34 and 32) to 32, and thence to contact-screw 36. There are therefore three supposable cases in the event of a break in the 30 line, namely: a dead-break and the grounding of either end, for we may lose sight of the possibility of both ends grounding at once. Until the break is repaired or the pins 31 are properly placed, the register continues to run. 35 In the event of a dead-break, the pin of relay 18 is lowered. Should the left end of the line ground, the pin in relay 17 is raised to the upper hole and that in 18 moved as before; and should the right end ground, the pins are undisturbed from their normal positions, only the 40 switch 19 and plugs 28 29 being moved. A minute's experimenting with the pins 31 determines the case in point, for there are but three possible arrangements of the pins to 45 meet any possible case. In the event of a break in either of the circuits, *a a'* or *b b'*, the plugs 26 and 27 are simply moved to the right, so as to set up connection between the upper half and right lower segments of their disks. 50 As above stated, the ground-connections of the various boxes are normally off, but provision is made for making and breaking circuit with the ground as the signal-box is operated. In Figs. 2 and 3 of the drawings is shown the 55 box mechanism for this purpose.

H is the base of the box, having the usual frame, *h*, train of clock-work, escape-wheel, crank *I*, and stop *j'*. It is furnished also with clamps *L' L''* for the main-line wire, one end 60 being soldered to the frame *h*, the other being attached to a lip, *k*, on the insulating-block *K*. The lip *k* bears on the periphery of a disk, *J'*, having notches to break and make circuit, whereby, when the disk revolves, the signal is 65 transmitted. So far as described the box is of the usual and well-known form. I add thereto

a ground-connection from the clamp *L*, and connect the latter with a second lip, *k'*, on the block *K*, adapted to make and break circuit with a second disk, *J*, soldered to the face of the disk *J'*, and concentric therewith. The disk *J* is smaller than the disk *J'*, and the lip *k'* does not touch its periphery. The disk, however, is provided with a number of properly-spaced teeth, *j*, which project far enough to touch the lip *k'* as the disk revolves, and make circuit. In operation as the crank is turned the arm *i* passes clear of the pin *j'* and the disks turn, sending the signal to the central office. As long as the line is intact the signals are transmitted thereby. The ground is thrown on at the box, but not at the central office. In case of a break in the line at either side, the operator throws on the ground at the office, and the current, entering the box by the unbroken wire-connection, returns through the ground as the box is operated.

The advantages of my system over those heretofore in use are apparent. The line may break; but it is in the power of the operator 90 at the central office to practically repair it instantly without leaving the office. Furthermore, my invention requires no revolution in the construction of existing lines in order to apply it. The plant is not disturbed at all, 95 the only change being one of addition, and that a simple and inexpensive one.

I have described my invention as applied to district-telegraph purposes; but it is obviously 100 equally applicable to fire-alarm telegraphs, hotel-annunciators, or other instances of a central office in communication with a number of stations and circuits.

I am aware that it is not new to ground the several stations of such systems, as well as the 105 central office—as, for instance, in the non-interfering fire-telegraph system—in which case each box in being operated short-circuits through the ground to the office and cuts out the boxes beyond; but that has nothing in 110 common with my invention except a ground-circuit, which is very old. A break in the wire of such a system cuts out the boxes beyond the break, and they remain inoperative until the break is repaired, whereas by my invention a break is instantly remediable at the 115 central office, and all the signals come in as if there were no break, and every possible contingency in the event of a break is provided for. This result I believe to have been hitherto unattained; and

I therefore claim as my invention and desire to secure by Letters Patent—

1. In a district or analogous telegraph system, a continuous metallic circuit connecting 125 the several stations with the central office, a battery adapted to be grounded in the center, and a switch for shunting said battery into circuit, in combination with a relay intermediate each pole of said battery and the termini 130 of the circuit, said relays working a local circuit register and gong, and having means for

changing their stroke from forward to backward, whereby, in the event of the breaking of the main line, the contingency of the grounding of either end of the line is provided for, 5 as and for the purpose set forth.

2. In combination with the conventional district-telegraph plant, a normally-open ground-connection for each box, and means for closing such connection, a central office having a 10 ground-connection from an extra battery, arranged to be shunted into circuit, and having a register and gong, and relays 17 18, having means for reversing their stroke, and the switch 19, as set forth.

15 3. In combination with the main-line wires of the closed metallic circuit, the extra battery 12, having ground-wire 30, and the relays 17 and 18, having disks 32 33 34, plugs 31, and connections from said disks with the local

battery, and the insulated pins and frame of 20 the relays, as set forth, whereby provision is made for every possible contingency in the event of a break in the line with respect to the grounding of either end.

4. In combination with the main line and 25 battery 12, the relays 17 18, on opposite sides of the battery, the double-lever switch 19, having ground 30 from the center of the battery, the relays 17 18, and wires 37 38, as set forth.

5. The box mechanism herein described, consisting of the notched disk J' and smaller toothed disk J , concentric therewith, lips k k' , and main line and ground connections, as set forth. 30

Corrections in Letters Patent No. 253,080.

It is hereby certified that in Letters Patent No. 253,080, granted January 31, 1882 to Chauncey F. McCulloh, of Baltimore, Md., for an improvement in "District Telegraph Systems," the word "break," in line 64, on page 1 of the printed specification attached to and forming a part of said Letters Patent was erroneously printed "brake;" that the proper corrections have been made in the files and records pertaining to the case in the Patent Office, and are hereby made in said Letters Patent.

Signed, countersigned, and sealed this 7th day of February, A. D. 1882.
